United States Patent Office.

PHINEAS JONES, OF NEWARK, NEW JERSEY.

Letters Patent No. 76,198, dated March 31, 1868.

IMPROVED THILL-COUPING.

The Schedule referred to in these Letters Patent and making part of the same.

TO ALL WHOM IT MAY CONCERN:

Be it known that I, PHINEAS JONES, of Newark, in the county of Essex, and State of New Jersey, have invented a new and improved Thill-Coupling for Vehicles; and I hereby declare the following to be a full and exact description thereof, reference being had to the accompanying drawings, which make a part of this specification, and in which—

Figure 1 represents a vertical longitudinal section of a thill-coupling illustrating my invention, and

Figure 2 a horizontal section of the same at xx , fig. 1.

Figure 3 is a vertical section, illustrating a modification in the manner of applying the thill-iron to the wood.

Similar letters of reference indicate corresponding parts in all the figures.

The nature of my invention consists in forming the rear end or loop of the thill-iron so thin as to constitute in itself a spring, which, by means of a bolt and nut, may be drawn tightly around an annular bushing of raw hide, leather, or other suitable material, which surrounds the coupling-bolt, and is compressed thereon with any necessary force, so as to protect the thill-iron from wear, and effectually prevent rattling. The device possesses several important advantages over those hitherto in use, as will be hereinafter more fully explained.

In the drawings, A represents a portion of the wooden thill, and B a portion of the thill-iron; the annular rear part of which, from b to b' , is formed of a uniform thinness, so as to constitute a spring. b^2 represents a rigid projection from the aforesaid elastic loop or band, and C a bolt, which, passing through to the body of the iron, B, and its end b^2 , receives a nut, D, by means of which the band b b' may be drawn as tightly as desired around the fillet or packing E, which encircles the coupling-bolt F. G represents the customary clip, formed with perforated ears, g g , for the reception of the bolt F. In fig. 1, the bolt C is represented as passing through the wooden part of the thill. In fig. 3, the said bolt is shown with its head countersunk into the iron, and a separate bolt, C', is shown, connecting the iron and the wood. My thin elastic band b b' affords room for a sleeve or bushing, E, of ample thickness to sustain all the wear from a coupling-bolt, and by being drawn in from time to time, will compress the said bushing constantly and uniformly around all parts of the said bolt. When released from the bolt C, the elasticity of the strap causes it to open around the entire circle, (as shown in red lines in fig. 3,) thus freeing the bushing more completely than in the case of a hinged strap, and admitting of the insertion of a bushing of larger size.

Where it is desired to change from shafts to tongue, or vice versa, the nut D is turned back sufficiently to allow the strap b b' to open, and the coupling-bolt F may then be readily taken out.

The above-described device is believed to combine the qualities of cheapness, simplicity, and efficiency in a greater degree than any heretofore contrived.

By forming the band b b' thick in the middle and thin at the edges, as indicated by the red line in fig. 2, and causing the bushing to project slightly, any metallic contact between the thill-iron and the clip may be avoided, the contact being with the bushing only.

I am aware that elastic metallic straps, with lugs on one or both ends for the reception of screw-bolts, have long been in use for various other purposes. I am also aware that hooks of various forms have been formed upon the ends of the thill-irons, and also that the thill-iron has been provided with a hinged strap to enclose the coupling-bolt. This is inferior to my invention, in that it does not withdraw the pressure of the strap from all around the coupling-bolt, so as to allow the latter to be taken out by a slight turning back of the tightening-screw. These devices I do not claim; but

What I do claim, and desire to secure by Letters Patent, is—

The combination of the metallic spring b b' , formed upon the thill-iron, the sleeve E, and the tightening-bolt C, when arranged and employed substantially as and for the purpose herein set forth.

PHINEAS JONES.
